UNITED STATES PATENT OFFICE.

FRANK A. WHEELER, OF PITTSBURG, PENNSYLVANIA.

CAR-WHEEL-ROLLING MILL.

SPECIFICATION forming part of Letters Patent No. 664,799, dated December 25, 1900.

Application filed November 15, 1899. Serial No. 737,026. (No model.)

To all whom it may concern:

Be it known that I, FRANK A. WHEELER, a citizen of the United States of America, residing at Pittsburg, in the county of Allegheny and State of Pennsylvania, have invented certain new and useful Improvements in Rolling-Mills, of which the following is a specification, reference being had therein to the accompanying drawings.

10 My invention relates to certain new and useful improvements in rolling-mills, and is particularly adapted for rolling circular shapes, such as car-wheels, car and locomotive wheel tires, pipe-flanges, &c.

15 The rolling-mill constructed in accordance with my invention involves a radical departure in its mode of operation and arrangement of parts from the mills of this character heretofore used for rolling forged blanks, 20 annular ingots, or blooms into circular shapes, car-wheels, and car and locomotive wheel tires.

25 One of the objects of my invention is to construct a mill of this character with a pair of adjustable rolls that while revolving will by means of suitable mechanism operate longitudinally toward each other and upon the inner face of the blank, ingot, or bloom, thereby forming the requisite web, plate, flange, or other internal shape which is desired in 30 any circular shape, car-wheel, or tire.

35 A further object of my invention is to provide a mill of this class with a pair of removable rolls for forming the web, plate, flange, or other internal shape of a circular shape, car-wheel, or tire.

40 A further object of my invention is to provide a mill of this class with a pair of interlocking rolls for forming the inner face of a circular shape, car-wheel, or tire.

45 A further object of my invention consists in constructing a mill of this character with a series of rolls which will completely form and finish the blank, ingot, or bloom into a circular shape, car-wheel, or tire without changing any of the rolls during the process 50 of rolling, thereby overcoming the objections heretofore existing in some mills or machines of this character and avoiding the use of independent roughing or blooming rolls previous to the finishing process.

55 A further object of my invention is to provide liner-plates of different thicknesses

which are adapted to be adjusted to one of the rolls forming the web, plate, flange, or other internal shape on the inner face of a circular shape, car-wheel, or tire. These liner-plates limit the lateral movement of the rolls toward each other and form the said web, plate, flange, or other internal shape of the desired thickness; furthermore, forming 60 to all intents and purposes a solid roll and a bearing when the rolls are interlocked.

A still further object of my invention is to construct and operate a mill or machine having a pair of rolls that while bearing upon 65 and forming the inner faces of the rim of a car-wheel will at the same time bear upon and compress the web or plate in a lateral direction as regards the hub of said wheel, enough metal being provided in the web or 70 plate as forged at the hammer or press to accommodate the expansion of the wheel-blank or bloom to the required diameter in that the said web or plate may be well worked by rolling and not drawn or attenuated, as would 75 be the case if the web or plate of the wheel-blank or bloom was forged or cast to finished size before rolling the blank or bloom to the required diameter. This feature of my invention is of particular importance and will 80 be referred to farther on in this specification.

A further object of my invention is in the adaptation of a pair of improved edging-rolls for forming the edges of a circular shape, car-wheel, or tire that my improved mill is adapted for, either or both of said rolls being driven directly or frictionally, preferably both driven, 85 and by any suitable means.

A further object of my invention is to provide a pair of improved edging-rolls, one of 90 which being fixed in immovable bearings in a carriage or frame which itself moves to accommodate the expanding circular shape, car-wheel, or tire as rolled, while the other edging-roll operates radially in movable bearings 95 suitably adjusted in an auxiliary carriage or frame in order to be adjusted to the varying widths of the object being rolled and while so adjusted is maintained in such a position that its axis is parallel, or practically so, with the 100 axis of its mate during all or any part of the operation of reducing an ingot or bloom to the required width.

A further object of my invention is to pro-

vide a movable bearing for one of a pair of improved edging-rolls by installing said roll within the casting forming the hydraulic cylinder which operates to force said roll against 5 one face of the circular shape, car-wheel, or tire that is being rolled, said cylinder forming, to all intents and purposes, a guide to carry said roll, the plunger and piston of the cylinder being fixed and immovable.

10 A further object of my invention is to provide a longitudinally-adjustable pass or groove in the rolls used to form the web, plate, flange, or other internal shape of a circular shape, car-wheel, or tire, said rolls while revolving being at the same time operated longitudinally toward each other by suitable power-motors, thereby decreasing the width of the pass or groove to the required distance and at the same time compressing or rolling 15 a portion of the ingot or bloom contained therein to the required shape of the inner faces.

15 A further object of my invention is to provide a pair of operating-shafts having adjustably secured to one of their ends a pair of rolls which are removable and adjustable longitudinally and adapted to form a web, plate, flange, or other internal shape on the inner face of the circular shape, car-wheel, or tire, 20 said rolls being also interlocking.

25 Briefly described, my invention consists in providing a mill of this character with a pair of interlocking, removable, and adjustable rolls adapted to form the desired web, plate, flange, or other internal shape on the inner face of a circular shape, car-wheel, or tire, said rolls while revolving having a longitudinal movement toward each other, a roll for forming the periphery of a circular shape, car- 30 wheel, or tire, said roll while revolving having a longitudinal or vertical movement against the periphery of a circular shape, car-wheel, or tire, a pair of edging-rolls for forming the edge of a circular shape, car-wheel, or tire, one 35 or two pairs of idler-rolls to guide the circular shape, car-wheel, or tire and keep it true and round, and means for operating said rolls simultaneously against the ingot or bloom during 40 the process of forming the same into a circular shape, car-wheel, or tire.

45 With the above and other objects in view my invention consists in the novel combination and arrangement of parts hereinafter more fully described, particularly pointed out 50 in the claims hereunto appended, and illustrated in the accompanying drawings, wherein like numerals of reference indicate corresponding parts throughout the several views, and in which—

55 60 Figures 1 and 1^a when taken together illustrate a side view of my improved mill. Fig. 1^b is a side elevation of my improved mill. Fig. 2 is an end view thereof. Figs. 3 and 3^a when taken together illustrate a top plan view 65 of my improved mill. Fig. 4 is a detail end view showing a portion of the mill above the lines *a a*, Fig. 2. Fig. 5 is a vertical sectional

view through the center of the mill. Fig. 6 is a longitudinal sectional view showing the edging-roll carriage or frame, the edging-rolls 70 and their operating-shafts suspended therein, and the auxiliary carriage or frame for the operating one of the edging-rolls. Fig. 7 is a top plan view of the edging-roll carriage or frame, showing the operating-shafts for the 75 rolls and the gearing for operating the same. Fig. 8 is a sectional view of the base-plate of the mill, showing the operating-cylinder for the main driven roll. Fig. 9 is a cross-sectional view showing the manner in which the 80 edging-roll housings are connected to the entablature of the mill. Fig. 10 is a cross-sectional view showing the means for adjusting the guide-blocks for steadyng or guiding the edging-roll carriage or frame. Fig. 11 is a 85 side plan view of my improved rolls, showing a vertical section of a bloom or ingot arranged between the same with but one-half revolution made. Fig. 12 is a vertical sectional view of my improved rolls and a bloom or ingot arranged between the same when finished. Fig. 90 13 is a vertical sectional view of my improved roll and a bloom or ingot as entered in the same and one-half revolution made. Fig. 14 is a vertical section of my improved rolls and 95 a bloom or ingot arranged between the same when finished. Fig. 15 is a cross-sectional view taken on the line *xx*, Fig. 3^a or Fig. 3. Figs. 16 and 16^a when taken together are a side 100 view of one of the operating-shafts and the supports and connections therefor, shown in section.

105 Referring to the drawings by reference-numerals, 1 and 2 indicate the operating-shafts for the web-rolls 3 and 4, which are adapted to form the fillet of the rim and the web of a car-wheel 5, as well as reduce said web to the required thickness. The inner end of each of the operating-shafts is provided with a substantially cone-shaped recess 6, in which 110 is secured the cone-shaped extension or shank 7, formed integral with one side of each of the web-rolls. 8 indicates an annular flange or collar formed upon the web-rolls at the jointure of the extension or shank with the 115 same. This flange or collar 8 forms a shoulder which abuts against the inner face of the operating-shaft.

120 Forming the shafts and web-rolls in the manner shown allows for the same to be removable.

125 The operating-shafts 1 and 2 are supported in suitable bearings 9 by means of the sleeves 10, which are secured to the shafts by the keys 11. These keys 11 are arranged within a longitudinal groove formed in the shafts and the sleeves, which are in alinement with each other. By this arrangement the shafts 1 and 2 are permitted to move longitudinally within the sleeves.

130 The shafts 1 and 2 are revolved by means of the pinion 12, which is or may be formed integral with each of the sleeves 10 and which meshes with the intermediate gear 13

upon the counter-shaft 14, mounted in suitable bearings. The gear-wheel 13 meshes with the pinion 14' upon the shaft 16. This shaft is mounted in the bearings 17 and has secured to its outer end the coupling 18 for driving the same frictionally by a suitable power-motor independent of the main operating means, or it may be coupled thereto and driven directly. The result of this arrangement of operating means for the rolls 3 and 4 is that they revolve at the speed desired and which is determined by the requirements of the object to be rolled, a change of speed being necessary from one condition to another, as is understood by those familiar with the art. The bearings 9 are supported in suitable housings and have mounted between the same and the sleeves 10 the babbitts or bushings 19.

By the arrangement of securing the shafts 1 and 2 within the sleeves 10 the same allows of a longitudinal movement while the shafts are revolving for the purpose of forcing the abutting ends of the shafts simultaneously together when suitably equipped with a working face such as is given thereto by the web-rolls. The object of this movement is to compress the web, plate, or other internal shape of a circular shape, car-wheel, or tire to the required thickness and to locate and fix the position of such internal shape as regards the outer face or periphery of the object to be rolled. To accomplish the longitudinal movement of the shafts 1 and 2, the same is obtained by connecting the outer end thereof to a suitable power-motor 20 or any other suitable appliance connected to the outer end of the shafts for obtaining such movement.

The power-motor 20, as shown, is provided with a suitable piston 21, connected at one face thereof to the piston-rod 22 and at its opposite face to the plunger-arm 23, which is connected, by means of the slideable coupling 24, to each operating-shaft. The coupling 24 is provided with the keys or fastening-pins 25 26, the key or pin 25 extending through one side of the coupling 24 and engaging in an annular groove 27, formed in the ends of each shaft, as shown. This allows for the revolving of the shaft. The key or pin 26 extends through one side of the coupling 24 and engages in a recess formed in the outer end of the plunger-arm. This secures the plunger-arm to the coupling and permits of longitudinally moving each of the operating-shafts. Arranged between the end of the shaft and the plunger-arm is a ball-race, in which is mounted the ball-bearings 28 for preventing friction. The key or pin 26 is somewhat smaller than the opening in the sliding coupling 24 to allow for a small play of the plunger-arm before moving the operating-shaft longitudinally. The coupling 24 is suitably supported by the bearing 29.

The outward movement of the shafts 1 and 2 is arrested by means of a shoulder 30, formed

upon each of the shafts, and the inward movement of the shafts 1 and 2 is arrested by means of the nut 31, mounted on the outer end of each piston-rod and engaging the annular flange 32 of the gland 33, abutting against the head 34 of the motor-cylinder. 35 indicates a suitable packing for the piston-rod, and 36 a suitable hand or turn wheel for the stop-nut. By providing the end of the piston-rods with the stop-nut 31 the longitudinal movement of the working face of each shaft can be adjusted for regulating the rolling of the web or other internal shape to the desired thickness.

In adapting the mill for rolling such tire, pipe, flanges, or other circular shapes as are cylindrical internally and not in the form of disks, such as car-wheels, I provide a pair of interlocking rolls—for example, as will be seen at 37 38, Figs. 13 and 14. Each of the rolls 37 38 is provided with a cone-shaped shank for securing the same in the inner end of the operating-shafts, forming thereby a shoulder 39, which abuts against the shafts, as shown. The working face of the roll 37 has an annular recess 40 of a suitable depth, in which are adapted to be removably secured, by means of the set-screws 41, liner-plates 42 of the desired thickness. The roll 38 is provided on its working face with an annular projection or tenon 43 of less diameter than the roll, forming a shoulder 44. The projection 43 engages within the annular recess 40 of the roll 37, and its movement is limited by means of the liner-plates 42, and arranged in the one face of the projection is a recess 44', in which engages the head of the set-screw 41. By this arrangement of interlocking or removable rolls the inner face of a tire 45 is formed with the flange 46. (See Figs. 13 and 14.)

It will be observed that owing to the arrangement of the annular recess in the roll 37 and the mounting therein of different-sized liner-plates the thickness or section of the flange, web, or other internal shape formed on the inner face of the tire or circular shape can be regulated as desired. Furthermore, during the operation of the rolls 37 38 the position of the flange, web, or other internal shape relative to the edge of the object rolled and the movement of the rolls can be limited by the stop-nuts 31, regulating the longitudinal movement of the operating-shafts.

The projection or tenon 43 of one roll operating within the annular recess of the opposite roll will prevent the rolls from being forced out of alignment by the pressure exerted by the main driven roll, to be hereinafter referred to, as the projection or tenon will act as a lock for the rolls, thereby making to all intents and purposes a solid roll with bearings at each end and keeping the rolls in their true relative position while so interlocked.

It will be evident to those skilled in the art that not only can the most difficult forms of circular shapes, car-wheels, or tires be rolled upon my improved mill with ease and

readiness, as has heretofore been referred to, but ordinary car and locomotive wheel tires and circular shapes of plain or straight faced or straight taper-faced inner surface or bore 5 can easily be rolled by simply using a pair of interlocking rolls with a plain periphery. In such instances the rolls should be made so that the joint between them is at one side of the metal being worked and not bearing 10 therein.

It is not intended to limit the construction of the operating-shafts so that their movement will be on the same general longitudinal line; but the said shafts may be set in 15 suitable housings at any angle that will permit the longitudinal lines of the movement of the shafts to meet a common center.

47 denotes a roll for forming the periphery or tread of a circular shape, and which I term 20 the "tread-roll." This roll in mills of this character is known as the "main" roll, and as used in my improved mill is adapted to have a movement other than that of revolving as it during its revolution is forced against 25 the ingot, bloom, or blank by a suitable power-motor, preferably hydraulic, as shown in Figs. 2 and 8, as at 48, the piston 49 of the motor being connected by its rod 50 operating through the motor-head 51 and the 30 stuffing-box 52, the cylinder 48 being mounted at the center of the base-plate 53 of the mill.

The tread-roll 47 is provided with the necks 54, one of which is elongated and forming 35 thereby an ordinary wabbler 55, to which is attached (not shown) a coupling-box and vibrating spindle, and the usual mill connections are employed (well known in the art) to connect the rolls with the main driving mechanism. 40

The tread-roll 47 is provided with the cradle 56, journaled and suitably fastened thereto. This cradle 56 has the piston-rod 50 connected to its lower face. This allows of the 45 tread-roll being forced against the ingot, bloom, or blank which encircles the web-rolls, thereby causing a reduction of the object rolled and enlarging it in diameter.

57 and 58 indicate my improved edging- 50 rolls for rolling the edges of the circular shapes, car-wheels, and tires. 57 indicates the back and 58 the front edging-roll.

59 indicates the operating-shaft for the roll 57, and 60 the operating-shaft for the roll 58, 55 and the lower ends of these shafts are provided with a substantially cone-shaped recess in which is secured the cone-shaped shank 61 of the rolls 57 58. (See dotted lines, Fig. 5.) By forming the shank 61 upon the edging- 60 rolls a shoulder is formed which abuts against the lower end of the shafts 59 60. This construction is the same as heretofore referred to in connection with the operating shafts 1 and 2 and the web-rolls and permits the edging-rolls to be removable or detachable to or 65 from their operating-shafts.

The shaft 59 for the edging-roll 57 while

revolving operates within suitable radial bearings 62, fixed within a movable carriage or frame 63. (See Fig. 6.)

The shaft 60 for the edging-roll 58 while revolving operates within suitable radial bearings 64, fixed within a movable housing 65, which is arranged and guided within the carriage or frame 63, the housing 65 having 75 an independent movement of the carriage or frame 63 at right angles to the same and perpendicular to the shaft 60, to which is attached the roll 58.

The shaft 59 for the roll 57 has no radial 80 movement and is intended to take the thrust of the shaft 60 with the roll 58 while the edges of the ingot, bloom, or blank are being reduced to the required width. The radial movement of the shaft 60 and the roll 58 is 85 adapted to direct the pressure exerted by the roll 58 upon the edges of the object being rolled, and such radial movement is obtained by the auxiliary housing or frame 65 operated in a suitable manner. This housing or 90 frame 65 has arranged therein a suitable hydraulic motor 66, having a piston 67 operating therein and connected by the rod 68 to a thrust-plate 69, suitably secured in one end of the carriage or frame 63.

The housing or frame 65 is rectangular in 95 contour to prevent the same from turning in the carriage or frame, which is provided in its top, at one side thereof, with an opening 70, through which projects the upwardly-extending guide 71, formed integral with the carriage or housing 65.

The thrust-plate 69 is so secured in the end of the carriage 65 as to allow of an easy withdrawal thereof when desired for removing the 100 auxiliary carriage or housing 65 from the carriage or frame 63.

72 indicates a stop for limiting the movement of the carriage or housing 65 by its motor 66, so that the width of the object being 110 rolled between the edging-rolls 57 58 will be as desired. This method of operating one of the edging-rolls in a mill of this character is novel and has a distinct advantage over the former construction used in mills of this class, 115 more specifically in that the movable edging-roll, such as 57, operates at all times in the same radial lines and at right angles to the surface being rolled, thereby avoiding distortion of the section of the object being rolled, 120 as is caused by similar rolls moving to their work in constantly-changing lines of force.

The edging - roll shafts are supported in 125 thrust-bearings, preferably ball or roller bearings 73, mounted in the slides 74 on the top of the carriage or frame 63. The use of such thrust-bearings removes all lateral pressure from the ends of the radial bearings 62 64 and tends to lessen friction and heating of the edging-roll-shaft bearings than is now the case.

In mills of this character heretofore but one of the edging-rolls has been driven directly from the main operating means and that one corresponding to the roll 57, the op-

posite edging-roll being an idler-roll. In my improved mill it is preferred to have both rolls driven directly or frictionally, either coupled together and both run at the same speed or 5 each roll driven independently, which is preferred and accomplished by means of the electric motors 75 76, connected to a suitable source of electric supply. The motor-shaft 77 of the motor 75 is journaled at its lower 10 end in the top of the carriage or frame 63 and at its upper end in the spider 78, while the motor-shaft 79 of the motor 76 is slidably journaled at its lower end in the guide 71 of the auxiliary carriage or housing 65 by means 15 of the step-bearing 80 and at its upper end journaled in the spider 82. The motor-shaft 77 is provided with a pinion 81, meshing with the intermediate gear 82, suitably supported by the carriage or frame 63 and which in turn meshes with the gear-wheel 83, mounted upon the edging-roll shaft 59. The upper end of the shaft 59 is journaled in the spider 78, as shown. The motor-shaft 79 is provided with a pinion 84, meshing with an intermediate 20 gear 85, slidably supported by the guide 71 of the auxiliary carriage 65 and which in turn meshes with the gear-wheel 86, mounted upon the edging-roll shaft 60. The upper end of the shaft 60 is journaled in the spider 82, as 25 shown. The ends of the spider 78 are connected to the stud or support 87, formed integral with the end of the carriage or frame 63, while the end of the spider 82 is connected to the stud or support 88, formed integral with the end of the auxiliary frame or housing 65.

The arrangement of edging-rolls and the operating means therefor will be found more satisfactory than the arrangement of and operating means for the edging-rolls heretofore 30 in use, wherein one of the two edging-rolls is driven direct from the main operating means, for while the main driven roll is new and of standard diameter and calculated to impart uniform speed to the said edging-roll, yet in 35 practice it is not possible to always maintain such uniform speed because of the wearing of the rolls necessitating turning down and a consequent reduction in diameter. It is advantageous on the score of economical operation to be able to use all the rolls of a mill until completely worn out.

It is evident that if the rolls vary from the standard in a mill for rolling circular shapes the object being rolled will either run too fast 40 or too slow for the edging-rolls and a slipping action is caused thereby that will either score the surface or distort or "cobble" the object rolled. In the manner of operating the edging-rolls as heretofore referred to it is evident that by means of a properly-devised table 45 of the relative speeds of the rolls referred to a sufficient speed can be imparted to the electric motors and to said rolls which will follow the speed of the ingot, bloom, or blank being 50 rolled to the effect that no slipping action will take place.

To compensate for the varying speed of the

main operating means or power-motor driving the main roll, an automatic device of any ordinary construction (not shown) is arranged to govern the relative speeds between said operating means for the main roll and the electric motors driving the edging-rolls. 70

To accommodate the expanding diameter of the ingot during the operation of rolling either longitudinally or vertically, I provide a series of hydraulic cylinders 89 of equal power, which are suitably supported in the manner shown and have their plungers 90 connected to the lugs 91, formed integral with 80 the carriage or frame 63, as shown at 92.

The manner of guiding the carriage or frame 65 within the housings 93 consists of a series of guide-blocks 94, provided with V-shaped teeth 95, meshing with correspondingly-shaped grooves 96 in the carriage or frame 63. The guide-blocks fit within grooves 96' (see Fig. 10) in the housings 93, as shown, and have their backs tapered in order that they may be forced down to take up the wear 90 on the teeth or to line up the carriage to its true center. The method of adjusting these guide-blocks is shown in Fig. 10 by means of the bolt 97 and guide 98.

To guide the ingot, bloom, or blank in a mill of this class and keep it true and round, the usual idler guide-rolls well known in the art are provided and as many may be used as desired; but preferably four are employed, a pair of which are termed the "upper" 100 guide-rolls 99 100, journaled in the brackets 101 and 102, and the remaining pair 103 104, called the "lower" guide-rolls, journaled in the brackets 104 105. Referring to the drawings, it will be seen that the rolls 99 and 100 105 are set at a uniform distance from the edging-rolls 57 58 and that the rolls 103 and 104 are set at a uniform distance from the web and tread rolls. The brackets for the upper guide-rolls are each connected to the carriage or frame 63 and move therewith, while the brackets for the lower guide-rolls are each connected to a slide-block 106, arranged in the housings, as shown. (See Fig. 5 of the drawings.) These blocks are each provided with 115 a screw 107, which is adapted to move the blocks and lower guide-rolls longitudinally within the housings by means of a suitable gearing and suitably coupled together by an ordinary counter-shaft, to the effect that both 120 lower guide-rolls are advanced or retired at will within the housings. Power is transmitted to the counter-shaft by a suitable friction-clutch or electric motor. (Not shown.)

The frame for my improved mill consists 125 of the intermediate base or bed plate 53', the floor-line of the mill being on a plane through said bed-plate, about the center thereof. This bed or base plate has a vertical opening through its center in which the tread-roll, 130 lower guide-rolls, and web-rolls operate upon the object being rolled. Within this base or bed plate 53' are the housings 108 for the operating-shafts and the housings 109 for the

lower guide-rolls. Suitably mortised in the bed or base plate 53' are the four standards 110, the bases of which are tenoned in the base-plate 53', binding all four standards together. The main or tread roll cradle is guided within the standards 110. On the top of the intermediate base or bed plate 53' are mortised therein the housings 93 for the guide-blocks 94 for the carriage or frame 63, and the top of these housings 93 are tenoned (not shown) in the entablature 111 for the binding of the same together. To bind this construction together, four tie-rods 112 run from the base-plate 53' through the center of the standards 110, the housings 93, and the entablature 111. These tie-rods have shoulders resting on top of the intermediate bed-plate 53', which, together with the tie-rods 113, shouldered in the same manner, serve to take the thrust of the power exerted by the tread-roll against the web-rolls, making that part of the mill self-contained and independent of that above the bed-plate 53'. Tie-rods 114, of a similar character to those heretofore referred to, extend in a horizontal plane from end to end of the mill through the intermediate bed-plate 53' and the housings 115 for the bearings 9 and the frame 116, integral with the cylinder 20, connecting the same together. They serve the purpose of taking the thrust of said cylinder 20, which operates the longitudinal movement of the operating-shafts 1 and 2.

While it is preferred to set the mill as shown in the general plan illustrated in Figs. 1, 1^a, 1^b, 2, 3, and 3^a, yet it may be operated as shown if inverted or set on edge at an angle of ninety degrees from its position as shown without deviating from the principles of construction and combination of rolls and parts as shown and described.

The operation of my improved mill or machine is as follows: The cylinders or motors 20, operating simultaneously, withdraw the operating-shafts 1 and 2, with the pair of web-rolls 3 4 or 37 38, as the case may be, within the housings out of the way of the object to be rolled as it is entered in the mill. The lower guide-rolls 103 104 are withdrawn into their housings 109. The edging-roll carriage or frame 63 is lifted out of the way by the power-cylinders 89, thus leaving a clear space for entering the ingot, bloom, or blank. The latter is properly heated and, held in suitable tongs, is entered at one side or the other of the mill and allowed to rest upon edge or the working face of the tread-roll 47, the latter having been lifted from below by the cylinder 48 to meet it. While the bloom is held in a vertical position, the cylinders 20, acting simultaneously, bring up the operating-shafts 1 and 2, with their attached rolls 3 4, if the object rolled is a car-wheel 5' or similar circular shape, and the ends of the rolls bear lightly upon the web or plate of the car-wheel ingot, bloom, or blank, just enough to steady it while the tongs are withdrawn.

The edging-rolls 57 58 are next lowered and encompass the ingot, bloom, or blank, the edging-roll 58 being first drawn back by the auxiliary carriage 65 to give enough space for the bloom to enter. After entering the bloom the edging-roll 58 is closed onto the bloom lightly. The lower guide-rolls are now run out of their housings and grasp and hold the bloom lightly. The tread-roll is then revolved by the main engines, slowly at first, but gradually increasing to the speed desired. As the bloom 5 revolves under the action of the tread-roll the web-rolls 3 4 are driven just enough by the electric or other motor driving them to follow the speed of the bloom on the inner surface. At the same time the cylinders 20 are simultaneously exerting a longitudinal motion to the operating-shafts 1 and 2, which in turn communicate that motion to the rolls 3 4, whose ends gradually reduce the outwardly-tapered web or plate of the bloom 5, as shown in Fig. 11. The metal in this web or plate, as shown in the ingot, bloom, or blank 5, is thicker than is required in the finished car-wheel 5', and this action of the rolls 3 4 is for the purpose of working the metal well in said web or plate and leaving it in a properly-worked condition necessary after the reheating and elongating or drawing action is set up by the increasing diameter of the rim of the wheel. Simultaneously with the above-described action of the rolls 3 4 the edging-rolls are reducing the bloom to the required width and keeping it in a vertical position, the upper guide-rolls 99 100 helping to keep the bloom round. The lower guide-rolls are now kept tight on the bloom for the same purpose. Gradually the pressure is applied to the bloom by the tread-roll and the speed of the main engines and the several motors increased until the result is a rolled car-wheel or similar circular shape of the required diameter.

In rolling tires or similar circular shapes the operation as above described is carried out with the exception that the interlocking rolls 37 38 are used, and while the bloom is held suspended in the tongs the tenon 43 of the roll 38 is entered in the hole in the bloom 45 and interlocked with the recessed face 40 of the roll 37, giving it an adjustable pass or groove. By means of this improved method considerable saving in cost can be made in the preparing of ingots, blooms, or blanks previous to rolling, as where two or three separate operations in the forging process are now necessary but one will be so needed.

I of course do not wish to limit myself to the construction in rolls for forming circular shapes, car-wheels, and tires from ingots, blooms, or blanks as set forth in the foregoing description and shown in the accompanying drawings, as it will be noted that various changes may be made in the details of construction without departing from the general spirit of my invention.

Having thus fully described my invention,

what I claim as new, and desire to secure by Letters Patent, is—

1. In a rolling-mill, a pair of operating-shafts mounted to rotate and move longitudinally during their rotation, a web-roll mounted in the end of each of said operating-shafts and adapted to endwise engage the web of a vertically-arranged car-wheel bloom or blank whereby the web of the car-wheel is completely rolled with a single pair of rolls, means for imparting rotary movement to said shafts and web-rolls, separate means for operating the shafts and web-rolls longitudinally during their rotation, and means for adjustably limiting the longitudinal movement of said shafts and rolls.

2. In a rolling-mill, a pair of operating-shafts mounted to rotate and move longitudinally during their rotation, a web-roll mounted in the adjacent ends of each of said shafts and adapted to endwise engage the web of a vertically-arranged wheel bloom or blank whereby the web of the car-wheel is completely rolled with but one pair of rolls, means for imparting rotary movement to said shafts and rolls, and separate means for operating the shafts and web-rolls longitudinally during their rotation, combined with a vertically-moving revolving tread-roll adapted to engage the periphery of said wheel bloom or blank and roll the same into a tread and flange, and a pair of vertically-moving revolving edging-rolls adapted to engage the rim of the wheel bloom or blank and roll the same to the desired thickness.

3. In a car-wheel-rolling mill, a pair of operating-shafts mounted in horizontal alinement with each other and adapted to rotate and move longitudinally during their rotation, a pair of interlocking web-rolls connected to the adjacent ends of said shafts, means for rotating said shafts and rolls, and means for moving the same longitudinally during their rotation.

4. In a car-wheel-rolling mill, the combination with a pair of operating-shafts mounted in suitable housings in horizontal alinement with each other and adapted to rotate and move longitudinally toward each other during their rotation, means for rotating said shafts, and means for moving the shafts longitudinally during their rotation, of a pair of interlocking web-rolls mounted in the adjacent ends of said shafts, said web-rolls being adapted to endwise engage the web of a vertically-disposed car-wheel bloom or blank, as and for the purpose described.

5. In a car-wheel-rolling mill, a pair of longitudinally-moving operating-shafts, a pair of interlocking web-rolls suitably connected thereto, and means for revolving said rolls.

6. In a car-wheel-rolling mill, a pair of operating-shafts, a pair of interlocking web-rolls suitably connected thereto, means for revolving said shafts and rolls, means for connecting said shafts to said operating means to permit of a longitudinal movement of the

shafts and rolls, and means connected to said shafts and adapted to move the rolls and shafts longitudinally while revolving.

7. In a car-wheel-rolling mill, a pair of operating-shafts, a pair of interlocking web-rolls mounted in the ends thereof, means for revolving said rolls and shafts simultaneously, means for connecting said shafts to said operating means to permit of a longitudinal movement, and means connected to said shafts and adapted to move the rolls and shafts longitudinally simultaneously with the revolution thereof.

8. In a car-wheel-rolling mill, a pair of rotating longitudinally-moving operating-shafts, an interlocking web-roll mounted in the end of each of the said shafts, means for operating said rolls and shafts simultaneously, and means for adjustably limiting the longitudinal movement of the said shafts and rolls.

9. In a car-wheel-rolling mill, a pair of operating-shafts supported in a suitable housing, an interlocking web-roll suitably connected to each of the said shafts, means for revolving said shafts and rolls, connections between said means and said shafts to permit of a longitudinal movement thereof, means for operating said shafts longitudinally while revolving, and connections between each of the said shafts and said means.

10. In a car-wheel-rolling mill, a pair of rotating longitudinally-moving operating-shafts, which are oppositely arranged and move toward each other during their rotation, and which are supported in a suitable housing, an interlocking web-roll suitably connected to each of the said shafts, means connected to each of the said shafts which rotates and permits an independent longitudinal movement thereof, operating means connected to the said means for rotating said shafts, and means connected to each of the said shafts for longitudinally moving the same.

11. In a car-wheel-rolling mill, a pair of rotating longitudinally-moving operating-shafts, which are oppositely arranged and move toward each other during their rotation, and which are supported in a suitable housing, a pair of interlocking web-rolls suitably connected to said shafts, means connected to each of the said shafts which rotates and permits an independent longitudinal movement thereof, operating means connected to said means for rotating said shafts, connections between said operating means for rotating said shafts simultaneously, and means connected to each of the said shafts for longitudinally moving the same.

12. In a rolling-mill, a pair of rotating longitudinally-moving operating-shafts, which are oppositely arranged and move toward each other during their rotation, and which are supported in a suitable housing, a pair of interlocking web-rolls suitably connected to said shafts, means for adjustably limiting the longitudinal movement of said rolls, means connected to each of the said shafts which ro-

tates and permits an independent longitudinal movement thereof, operating means connected to said means for rotating said shafts, connections between said operating means for 5 rotating said shafts simultaneously, and means connected to each of said shafts for longitudinally moving the same.

13. In a rolling-mill, a pair of rotating longitudinally-moving operating-shafts, which 10 are oppositely arranged and move toward each other during their rotation, and which are supported in a suitable housing, a pair of interlocking web-rolls suitably connected to the said shafts, means connected to each of 15 said shafts which rotates and permits an independent longitudinal movement thereof, operating means connected to said means for rotating the shafts, connections between said operating means for rotating said shafts simultaneously, and means for adjustably limiting the longitudinal movement of the said shafts.

14. In a rolling-mill, a pair of rotating longitudinally-moving operating-shafts, which 25 are oppositely arranged and move toward each other during their rotation and which are supported in suitable housing, a pair of removable web-rolls mounted in the adjacent ends of said shafts, means connected to each 30 of said shafts permitting a rotating and longitudinal movement thereof, gears connected to said means for rotating said shafts, connections between said gears for rotating said shafts simultaneously, means connected to 35 each of the said shafts for longitudinally moving the same, and means for adjustably limiting the longitudinal movement of the shafts.

15. In a car-wheel-rolling mill, the combination with a pair of rotating and longitudinally-moving operating-shafts, and operating means therefor, of a pair of interlocking web-rolls connected to said shafts and endwise engaging the web of a vertically-positioned blank, and a tread-roll arranged in 45 suitable relation with said web-rolls.

16. In a car-wheel-rolling mill, the combination with a pair of simultaneously-rotating and longitudinally-moving operating-shafts, and means for operating said shafts, of a pair 50 of removable web-rolls mounted in the adjacent ends of said shafts and adapted to rotate in unison therewith, a rotating and vertically-moving tread-roll, means for operating said tread-roll, a pair of edging-rolls, and separate 55 operating means for each of the said edging-rolls.

17. In a car-wheel-rolling mill, a pair of rotating and longitudinally-moving operating-shafts, operating means therefor, a pair 60 of interlocking web-rolls connected thereto and operating therewith, a rotating and vertically-moving tread-roll, and operating means therefor.

18. In a rolling-mill, a pair of simultaneously-rotating longitudinally-moving operating-shafts, operating means therefor, a pair 65 of web-rolls connected thereto and operating

therewith, a rotating and vertically-moving tread-roll, operating means therefor, a carriage or frame, an auxiliary carriage arranged therein, an edging-roll connected to each of said carriages, and separate means for operating each of the said edging-rolls.

19. In a rolling-mill, a pair of rotating and longitudinally-moving operating-shafts, operating means therefor, a pair of web-rolls connected thereto and operating therewith, a rotating and vertically-moving tread-roll, operating means therefor, a carriage or frame, a longitudinally-moving auxiliary carriage arranged therein, operating means for said auxiliary carriage, an edging-roll connected to each of the said carriages, and separate operating means for each of the said edging-rolls.

20. In a rolling-mill, a pair of simultaneously-rotating longitudinally-moving operating-shafts, operating means therefor, a pair of web-rolls connected thereto and operating therewith, a rotating and vertically-moving tread-roll, operating means therefor, a carriage or frame, a longitudinally-moving auxiliary carriage arranged therein, an edging-roll connected to each of the said carriages, separate operating means for each of the said edging-rolls, and means for elevating and lowering said carriages simultaneously.

21. In a rolling-mill, a pair of rotating and longitudinally-moving operating-shafts, operating means therefor, a pair of web-rolls connected to said shafts and operating therewith, a rotating and vertically-moving tread-roll, operating means therefor, a carriage or frame, a longitudinally-moving auxiliary carriage arranged therein, operating means for said auxiliary carriage, an edging-roll connected to each of said carriages, separate operating means for each of the said edging-rolls, means for elevating or lowering said carriage or frame, and suitable guiding means for the said carriage or frame.

22. In a rolling-mill, a pair of edging-rolls, a carriage or frame for one of said rolls, an auxiliary carriage for the other of said rolls mounted in the said carriage or frame, means for longitudinally moving said auxiliary carriage, means mounted upon the said carriage or frame and connected to one of said rolls for operating the same, means mounted upon the auxiliary carriage and connected to the other roll for operating the same, and means for elevating and lowering the said carriages.

23. In a rolling-mill, a pair of edging-rolls, means for operating each of said rolls independently of the other roll, means for moving one of said rolls laterally toward the other roll, and means for elevating and lowering said rolls simultaneously.

24. In a rolling-mill, a carriage or frame, an edging-roll, means carried by the said carriage or frame and connected to said roll for operating the same, an auxiliary carriage mounted in said carriage or frame, an edging-roll, means carried by the said auxiliary car-

- riage and connected to last-named edging-roll for operating the same, and means for simultaneously elevating and lowering the said rolls.
- 5 25. In a rolling-mill, a carriage or frame, an edging-roll, means carried by the said carriage and connected to said roll for operating the same, an auxiliary carriage mounted in said carriage or frame, an edging-roll, means 10 carried by said auxiliary carriage and connected to last-named edging-roll for operating the same, means for longitudinally moving said auxiliary carriage toward the first-mentioned edging-roll, and means connected 15 to the said carriage or frame for simultaneously elevating and lowering said rolls.
26. In a rolling-mill, the combination of a pair of edging-rolls one of which is mounted to rotate in a vertically-moving bearing and 20 the other of which is mounted to rotate in a horizontally-slidable bearing, means for operating each of said rolls independently of the other roll, and means for elevating or lowering the said rolls simultaneously with 25 each other.
27. In a rolling-mill, a pair of vertically-disposed and rotatable operating-shafts, a removable edging-roll connected to the lower end of each of said shafts, radial bearings and 30 thrust-bearings in which each of the said shafts are journaled, independent operating means for each of said shafts, means for moving one of said shafts and rolls toward the other shaft and its roll, and means for simultaneously elevating and lowering the said 35 rolls.
28. In a rolling-mill, a carriage or frame, an auxiliary carriage arranged therein, an operating-shaft suitably supported by the said 40 carriage or frame, an operating-shaft suitably supported by said auxiliary carriage, an edging-roll connected to each of the said operating-shafts, operating means carried by the 45 said carriage or frame for the said shaft carried thereby, operating means carried by the said auxiliary carriage for the shaft carried thereby, means for longitudinally moving said auxiliary carriage, and means for simultaneously elevating and lowering the said 50 carriages.
29. In a rolling-mill, a carriage or frame, an auxiliary carriage arranged therein, an operating-shaft supported by the said carriage or frame and journaled in radial and thrust 55 bearings, an operating-shaft supported by the said auxiliary carriage and journaled in radial and thrust bearings, operating means carried by the said carriage or frame for the said shaft supported thereby, operating means 60 carried by the said auxiliary carriage for the shaft supported thereby, means for longitudinally moving said auxiliary carriage, and means for simultaneously elevating and lowering the said carriages.
- 65 30. In a rolling-mill, a carriage or frame, an auxiliary carriage arranged therein, an operating-shaft supported by the said carriage or frame and journaled in radial and thrust bearings, an operating-shaft supported by the said auxiliary carriage and journaled in radial and thrust bearings, operating means carried by the said carriage or frame for the shaft supported thereby, operating means carried by the said auxiliary carriage for the shaft supported thereby, means for longitudinally moving said auxiliary carriage, and means for simultaneously elevating and lowering the said carriages.
31. In a car-wheel-rolling mill, a pair of rotating longitudinally-moving interlocking 80 web-rolls, and means for simultaneously operating the said rolls.
32. In a car-wheel-rolling mill, a pair of rotating longitudinally-moving interlocking web-rolls, means for limiting the movement 85 of one roll within the other, and means for simultaneously operating said rolls.
33. In a car-wheel-rolling mill, a pair of rotating longitudinally-moving interlocking web-rolls adapted to be interlocked at one 90 side of the metal being worked upon, means for limiting the movement of one roll within the other, operating means for said rolls, and means for longitudinally moving the said rolls simultaneously.
34. In a rolling-mill, an intermediate bed-plate 53', a base-plate 53, a series of standards 110 supporting said bed-plate and mounted upon said base-plate 53, a series of housings 93 supported by the bed-plate 53', an entablature connecting the said housings, a series of tie-rods extending through the said bed-plate 53', base-plate 53, standards 110, housings 93, and an entablature suitably secured thereto, a series of tie-rods 113 connected to said housings 93 and bed-plate 53', a housing 115, a frame 116, and a series of tie-rods 114 extending through said bed-plate 53', housing 115, frame 116, and connected thereto, substantially as shown and described.
35. In a rolling-mill, a pair of rotating longitudinally-moving web-rolls, means for operating the same, a rotating and vertically-moving tread-roll, suitable operating means therefor, a pair of lower adjustable guide-rolls, means for operating the same, a carriage or frame, a pair of edging-rolls carried thereby, separate means for operating each of the said edging-rolls, a pair of upper guide-rolls carried by the said carriage, and means for elevating and lowering said carriage.
36. In a rolling-mill, a pair of rotating longitudinally-moving web-rolls, means for operating the same, a rotating and vertically-moving tread-roll, suitable operating means therefor, a pair of lower adjustable guide-rolls, means for operating the same, a carriage or frame, a pair of edging-rolls carried thereby, separate means for operating each of the said edging-rolls, a pair of upper guide-rolls carried by the said carriage, and means for elevating and lowering said carriage.
37. In a rolling-mill, a pair of rotating longitudinally-moving web-rolls, means for op-

- erating the same, a rotating and vertically-moving tread-roll, suitable operating means therefor, a pair of lower adjustable guide-rolls, means for operating the same, a carriage or frame, an edging-roll carried thereby, operating means for said roll, an auxiliary carriage mounted in the said carriage or frame, means for longitudinally moving said auxiliary carriage, an edging-roll carried by 5
said auxiliary carriage, separate operating means therefor, a pair of upper guide-rolls suitably connected to said carriage or frame, and means for elevating and lowering said carriage or frame.
- 15 38. In a rolling-mill, a pair of operating-shafts, a web-roll connected to each of the said shafts, means for rotating said shafts and rolls, means for longitudinally moving said shafts and rolls while rotating, means 20 for limiting the longitudinal movement of the

said shafts, a rotating and vertically-moving tread-roll, suitable operating means therefor, a pair of lower adjustable guide-rolls, means for operating the same, a carriage or frame, an edging-roll carried thereby, operating means 25 for said roll, an auxiliary carriage mounted in said carriage or frame, means for longitudinally moving said auxiliary carriage, an edging-roll carried by said auxiliary carriage, operating means for the edging-roll carried 30 by said auxiliary carriage, a pair of upper guide-rolls suitably connected to said carriage or frame, and means for elevating and lowering said carriage or frame.

In testimony whereof I affix my signature 35
in the presence of two witnesses.

FRANK A. WHEELER.
